FLOAT-CONTROLLED VALVE

Frederick Henry Warner, Ipswich, England

Application March 27, 1931, Serial No. 525,794,
and in Great Britain May 9, 1930

2 Claims. (Cl. 137—104)

This invention comprises improvements in or relating to float-controlled mechanism which is automatically operated when the liquid in a container reaches a predetermined level, and 5 the invention is more particularly concerned with ball and valve mechanism of the kind used in conjunction with water supply cisterns.

In ordinary apparatus of this kind the float gradually rises with the liquid entering the container until a point below the predetermined level 10 is reached at which it starts to actuate the valve, but the valve is not completely closed till later, and conversely as the float sinks from the high level the valve is not completely opened 15 until this point is reached again. This slow actuation of the valve is undesirable.

With a view to avoiding this slow actuation of the liquid supply-valve, apparatus has been proposed in which the said valve is operated 20 automatically by a float in an auxiliary receptacle which is provided with an inlet of large area in relation to its capacity to receive liquid which overflows suddenly from the main liquid container when the predetermined high-level is 25 reached, so that the auxiliary receptacle is caused to fill quicker than the container and the liquid supply valve is correspondingly quickly closed. The proposed auxiliary receptacle was to contain an outlet and a valve 30 therefor opened by a low level float in the main liquid container upon the liquid reaching a predetermined low level for the purpose of causing the float in the auxiliary receptacle to fall rapidly and thus open the valve quickly. 35 One object of the present invention is to improve this known apparatus in such a way as to insure complete closure of the inlet valve during the whole period in which the fall of liquid is occurring so that complete discharge of the 40 liquid which is between the two levels can occur before a fresh influx begins.

Another object of the invention is to provide a simple and compact construction which avoids the necessity for any linkage or other 45 operative connection between the low level float and the valve controlling the outlet from the auxiliary receptacle aforesaid.

Accordingly the present invention provides 50 float-controlled mechanism for a liquid container comprising the combination with a float, a receptacle surrounding the float provided with an overflow inlet of large area in relation to its capacity at the level of the predetermined upper limit of liquid level in the container, and an 55 outlet in the bottom of the receptacle, of a low

level float, a valve member upon the low level float for controlling said outlet, and a basin upon the upper face of the low level float arranged to collect liquid issuing from the receptacle and to assist opening of the outlet valve 60 thereof.

It is also preferable to provide in the basin a drainage opening to effect unloading of the low-level float prior to the opening of the aforesaid valve in the receptacle-outlet but at a rate 65 substantially less than that at which the basin on the float receives the aforesaid liquid loading.

The present invention prevents any balanced state arising wherein the auxiliary receptacle might be filled as fast as it is being emptied 70 by its outlet valve, which would reintroduce the disadvantage the apparatus is intended to avoid.

One example of apparatus according to this invention will now be described with reference to 75 the accompanying drawing in which:—

Figure 1 shows in elevation a liquid supply tank fitted with the float controlling device, and

Figure 2 is a section of the said device taken 80 on the line 2—2 of Figure 1.

Referring to Figure 1, a liquid supply tank 10 is fitted with a float-controlled valve of the ball-valve type, and has mounted within it a fixed receptacle 11 in the form of a bowl within which the ball 12 can move vertically. The receptacle is mounted, as shown in Figure 2, on a bracket 13 fixed to the side of the tank with the upper rim 14 of the receptacle at the predetermined high level 140. An outlet 15 is provided in the bottom of the receptacle large enough to permit rapid emptying thereof. The outlet is controlled by a valve operated by a float 16 in the manner to be described hereinafter.

The valve comprises an externally screw-threaded tubular member 17 held vertically within an opening in the bottom of the receptacle by lock-nuts 18 and 19, and a flat annular valve member 20 having a rubber washer 21 adapted to rest on a valve seating 22 formed at the bottom of the tubular member. The rubber washer is held in position by a nut 23. The valve member 20 is formed integrally with a valve stem 24 slidable within a guide 25 secured within, or formed integrally with, the tubular member 17. A fibre washer 26 is secured by means of a bolt 27 to the upper end of the valve stem to limit its downward movement in the guide, its upward movement being limited by the closing of the valve when the float ascends. 110

The lock-nuts 18 and 19 serve also to compress a rubber washer 28 against the bottom of the inside of the receptacle to complete a liquid-tight joint there around the tubular member 17, 5 and to secure the receptacle to the bracket 13.

The float 16 has at the centre of its upper face a boss 29 for screwthreaded attachment of the float to the valve stem by means of a bolt 30. A receiver is formed on the upper face of 10 the float by securing an upstanding annular wall 31, around the edge of the said face, and a drain hole or pipe 32 is provided in the wall 31 substantially at the level of the upper face. The float 16 is located at such a height above the 15 bottom of the tank that it will descend to effect partial opening of the outlet 15 when the predetermined low level of liquid is attained in the tank.

The mode of operation of the apparatus is as 20 follows:—

Assuming that the supply cock 33 is open with the ball 12 in its low position as shown in the drawing, and the level of liquid in the tank is rising. As the liquid level ascends the float 16 25 also rises to close the outlet 15 and prevent liquid entering the receptacle at the bottom. When the predetermined high level 140 is slightly exceeded liquid will overflow suddenly from the tank into the receptacle which becomes 30 rapidly filled causing the ball 12 to rise rapidly and close the supply cock 33. When, upon withdrawal of liquid from the tank, the predetermined low level is attained the float 16 from which liquid will have drained through the drain 35 hole 32, sinks slowly with the liquid and commences to open the outlet 15 in the receptacle. The liquid issuing from the receptacle through the partially opened outlet fills the float-receiver and loads the float sufficiently to ensure rapid 40 and complete opening of the outlet 15. A shroud 34 is provided to direct the water coming through valve 15 downwardly into the receiver 31. This in turn causes rapid emptying of the receptacle and reduces the likelihood of incomplete opening of the outlet due to sticking of the 45 moving parts. The rapid emptying of the receptacle is desirable to ensure rapid opening of the supply cock when the ball 12 descends. Obviously, the size of the drain hole must be such 50 that liquid drains away more slowly than it enters even though the outlet 15 is not completely open.

Liquid now enters the tank and as the liquid level rises again it lifts the float 16 which in 55 turn closes the outlet 15. When the predeter-

mined high level is again exceeded liquid overflows into the receptacle and the cycle of operations is repeated.

It is to be understood that the invention is not limited to floats controlling a valve as described 80 in the specific example, but it is also applicable to apparatus in which other float-controlled mechanism is actuated when the liquid in a container reaches a predetermined high or low level.

Such mechanism may comprise a valve controlling the supply of steam to a steam-driven water pump used to supply water to a container, or the passage of gas when gases are measured by displacement of water.

I claim:—

1. Float-controlled mechanism for a liquid container, comprising the combination with a float and a receptacle surrounding the float provided with an overflow inlet of large area in relation to its capacity at the level of the predetermined upper limit of liquid level in the container and with an opening in the bottom thereof, of a tubular member mounted vertically within said opening, a low level float located below the tubular member, a disc-like 100 valve member mounted on the low level float for controlling the lower end of the tubular member, a valve stem integral with the valve member, a guide within the tubular member for the valve stem, an upstanding annular wall around 105 the upper face of the low level float and a drainage opening in said upstanding wall substantially at the level of the upper face of the low level float.

2. In a liquid container, float-controlled mech- 110 anism comprising the combination with a float and a receptacle surrounding the float provided with an overflow inlet of large area in relation to its capacity at the level of the predetermined upper limit of liquid level in the container and 115 with an outlet opening in the bottom thereof, of a bracket fixed to the container for supporting said receptacle, a tubular member mounted vertically within said outlet opening, a hemispherical low level float below the tubular member, a 120 valve member mounted on the upper flat face of the low level float for controlling the lower end of the tubular member, an upstanding annular wall around the edge of the flat face of the low level float, and a tubular shroud depending from 125 the bracket aforesaid and surrounding the valve member and the outlet from said tubular member to direct liquid coming through the tubular member into the basin.
